US0D1016301S

(12) **United States Design Patent** (10) Patent No.: **US D1,016,301 S**
(45) Date of Patent: ** Feb. 27, 2024

(54) **WOUND DRESSING**

(71) Applicant: **Medtrade Products Limited**, Cheshire (GB)

(72) Inventors: **Jordan Fisk**, Cheshire (GB); **Nicola Deeley**, Winsford (GB)

(73) Assignee: **MEDTRADE PRODUCTS LIMITED**, Cheshire (GB)

(**) Term: **15 Years**

(21) Appl. No.: **35/514,216**

(22) Filed: **Dec. 17, 2021**

(80) **Hague Agreement Data**

Int. Filing Date: **Dec. 17, 2021**

Int. Reg. No.: **DM/220468**

Int. Reg. Date: **Dec. 17, 2021**

Int. Reg. Pub. Date: **May 6, 2022**

(51) **LOC (14) Cl.** 24-02

(52) **U.S. Cl.**

USPC **D24/189**

(58) **Field of Classification Search**

USPC D24/189, 190, 110; D27/101

CPC A61F 5/3738; A61F 5/373
